UNITED STATES PATENT OFFICE

2,597,224

DRAPERY TRACK AND ROLLER ASSEMBLY

Charles Stanfield Charron, Toronto, Ontario, and
Alexander James Garvin, Scarboro, Ontario,
Canada

Application October 21, 1950, Serial No. 191,416

3 Claims. (Cl. 16—87.6)

1

This invention relates to a drapery track and to means employed in combination therewith for suspending drapery over windows or the like.

Prior types of drapery track are generally derived from a track section similar in form to a structural "I-beam" wherein a pair of wheels or discs ride between the flanges of the beam-like section on either side of the web thereof and a metal loop forming an axis for each extends downwardly to form a member joining between the two. A particular disadvantage of such construction is that it is not feasible to produce the same in a variety of colours for operability cannot be ensured if the track is painted. In any case, wear on painted parts will show to the under metal in time. Moreover, the small discs or rollers present relatively large side surfaces to the web of the section resulting in undue friction. Other types of drapery track departing from an I-beam type of section present some difficulty in connecting the drapery hanger device to the rolling means such as the wheels, discs, or the like employed, jamming of the device often being experienced. Another difficulty encountered with prior types of drapery track construction is the problem of joining pieces of track to ensure a smooth running past the joint as well as supplying sufficient strength therein.

Having regard to the foregoing other objects of the invention will be appreciated by a study of the following specification taken in conjunction with the accompanying drawings.

In the drawings—

Figure 1 is an enlarged sectional view of a drapery track according to the invention showing a joining bar therein along with suitable rollers and a drapery loop connecting device mounted therein.

Figure 2 is a sectional view on the line 2—2 of Figure 1.

Figure 3 illustrates the form of rollers and loop which may be employed in the track of the invention.

Figure 4 illustrates the assembly of the rollers and loop in the track.

Figure 5 is a perspective view illustrating the manner of joining separate pieces of track and also indicating the method of suspending the track from a wall surface or the like.

Referring in more detail to the drawings, the drapery track of the invention is illustrated in Figure 1 and comprises a body 10 preferably extruded of a suitable aluminum alloy and generally of a sectional form conforming to the letter H. The side walls 11 extend from the joining or cross

2

wall 12 upwardly to terminate in inwardly directed flanges 13 along the upper edge thereof. This upper region of the section is designed to accommodate a joining bar 14 which may be threaded as at 15 to accommodate a screw 16 which passes through a hole 17 in a mounting bracket 18 to firmly support the track by gripping the flanges 13 between the mounting bracket 18 and the joining bar 14.

10 The lower portion of the track below the cross wall 12 is designed to accommodate suitable roller means 19 preferably in the form of spaced apart rollers 20 joined by an integral reduced diameter portion or axle 21. The rollers 20 are of a diameter less than the dimension between the cross wall 12 and the inwardly directed roller supporting flanges 22 which extend inwardly from the lower edges 23 of the side walls 11. It is important to observe that the flanges 22 extend 15 inwardly to a projecting edge 24, which latter is in turn disposed inwardly of the inner surfaces 25 of the rollers 20. This is an important characteristic for a drapery loop 26 being fashioned of a simple loop of wire as illustrated in Figure 3 20 is simply suspended on the axle 21 and is prevented from binding with the rollers by said projecting edge as indicated by the position of the loop illustrated by chain lines 27 in Figure 1.

Another feature of the loop 26 is that the suspending arm portion 28 is of small radius as compared with the radius of the drape hanging portion 29. By reason of this feature, the suspending arm portion cannot be twisted to bind on the surfaces 25 of the opposed rollers 20 since the

35 depending portion of the loop will engage with the projecting edge 24 of the supporting flanges 22. It will thus be appreciated that the said projecting edges guard against binding in two directions of movement of the drapery loops 26. Moreover,

40 it will be seen that by reason of the small diameter of the suspending portion of the loop members the rollers may crowd together along the track without interference between the upper portions of the drapery loops. The lower portions of relatively large radius will, however, tend to interfere

45 with one another but in that free space below the slot of the track, so that the drapery loops may tip in various arrangements slightly to allow a slight overlapping of the lower end portions of the drapery loop.

50 It will be observed that the side walls 11 of the drapery track are undulated in section. This is not mandatory for the contour of the outer surfaces which may carry beading or any other suitable decoration as desired. Having regard

to the inner surfaces of the track, however, it is important to reduce friction to a minimum. In this respect the walls 11 are curved outwardly as at 30 and 31 to provide clearance with the outer surfaces 32 of the rollers 20. Of particular importance, however, is the arcuate clearance face 33 forming what is termed herein a roll pip channel. The inward projections 34 and 35 slidably engage the outer surfaces 32 of the rollers, but the slideable engagement is free in nature. The function of the roll pip channel is to allow free accommodation of a small spur 36 on each roller, known as a "pip" in machine shop practice, and which is derived from the machining of such rollers in an automatic lathe or the like. The incorporation of the roll pip channel thus eliminates the necessity of grinding or otherwise finishing the outer surfaces 32 of the rollers 20.

The manner of joining the drapery track of the invention is illustrated in Figure 5, wherein the track 31 of the form of the invention is suspended from a mounting bracket 38 in the manner illustrated in Figure 1. In this case, the joining bar 39 carrying a screw 40 threaded therein projects from the track 31 to receive a track 41. The slot 42 of the latter between the inwardly directed flanges 43 thereof passes about the shank 44 of the screw 40 in assembly and the latter is tightened down to bear upon the flanges 43 when the tracks have been brought into close assembled relationship.

One form of drapery track according to the invention has been disclosed in detail in order to facilitate an understanding of the principles thereof. The specific form of extruded track herein is subject to considerable modification in exterior contour and also in interior contour from the specific form shown.

What we claim as our invention is:

1. A drapery track and roller assembly, comprising in combination: a pair of spaced apart rollers of predetermined diameter and a common axle of relatively small diameter extending therebetween, track means including inwardly directed supporting flanges carrying said rollers, the terminal edges of said flanges being spaced to provide a slot therebetween of a width less than the distance between said rollers, a drapery loop member formed of a rigid material of circular cross-section and suspended from said axle by a suspending portion having a curvature, the

inner radius of which is slightly greater than the radius of said axle, the median radius being not greater than one-half the combined radius of a roller and axle, arms forming a part of said loop member extending tangentially from the suspending portion thereof through said slot and diverging sufficiently to provide engagement of said arms with the edges of said slot and entirely avoiding binding of said arms with said rollers and binding of said suspending portion with said axle upon twisting of said loop member.

2. A drapery track and roller assembly as claimed in claim 1, and a free end on said loop formed on a diameter larger than the diameter of one of said rollers and formed on the outward ends of said arms to depend below said slot.

3. A drapery track and roller assembly as claimed in claim 1, side walls forming a part of said track means for supporting said flanges and enclosing said rollers, and a roll pip channel in said side walls located lengthwise of said track and on the axial line of said rollers designed to freely accommodate without binding any small projections extending from the region of the axis 25 of the outer face of each roller.
